[57] **CLAIM**

The ornamental design for a fiber optic light source, as shown and described.

DESCRIPTION

FIG. 1 is a perspective view of a fiber optic light source embodying our new design;

FIG. 2 is a front elevational view of the fiber optic light source;

FIG. 3 is a rear elevational view of the fiber optic light source;

FIG. 4 is a top plan view of the fiber optic light source; and

FIG. 5 is a right side elevational view of the fiber optic light source, the left side of the fiber optic light source being similar.

FIG. 1

FIG. 2

FIG. 3

FIG. 4

FIG. 5
